HAIR CURLER

Tomme B. Sparks, Denver, Colo.

Application February 3, 1949, Serial No. 656

Term of patent 7 years

(Cl. D86—10)

To all whom it may concern:

Be it known that I, Tomme B. Sparks, a citizen of the United States of America, residing at Denver, in the county of Denver and State of Colorado, have invented a new, original, and ornamental Design for a Hair Curler, of which the following is a specification, reference being had to the accompanying drawing, forming part thereof.

Figure 1 is a perspective view of a hair curler, showing my new design.

Figure 2 is an end view thereof, taken in the direction of arrow 2 in Figure 1.

Figure 3 is a cross-sectional view, taken substantially in the plane of the line 3—3 in Figure 1, and

Figure 4 is a cross-sectional view, taken substantially in the plane of the line 4—4 in Figure 1.

I claim:

The ornamental design for a hair curler, as shown.

TOMME B. SPARKS.
